UNITED STATES PATENT OFFICE.

WARREN C. FISHER, OF MOUNT VERNON, IOWA.

DESIGN FOR A PICTURE-MAT.

SPECIFICATION forming part of Design No. 34,871, dated July 30, 1901.

Application filed June 22, 1901. Serial No. 65,700. Term of patent 7 years.

To all whom it may concern:

Be it known that I, WARREN C. FISHER, a citizen of the United States, residing and with post-office address at Mount Vernon, in the 5 county of Linn and State of Iowa, have invented a new and original Design for a Picture-Mat, of which the following is a specification, reference being had to the accompanying drawings, in which—

10 Figure 1 of the drawings is a front elevation of a picture-mat constructed and designed in accordance with my invention. Fig. 2 is a cross-section of the same.

Referring now to the drawings by numerals, 1 designates a flat oval-shaped body provided with an opening or cut-out portion 2 in the center thereof. A flag or streamer 3 is designed at one end of the body 1 and is suspended from a staff 4, which terminates at

one edge of the cut-out portion and continues 20 from the opposite edge. Immediately below the cut-out portion 2 of the mat is a representation of a line of stitching, (designated by the reference-numeral 5.)

The design above described may be printed, 25 painted, pressed into paper, wood, metal, or any suitable material, or may be cast from a mold.

What I claim, and desire to secure by Letters Patent, is—

30 The design for a picture-mat, substantially as herein shown and described.

In testimony whereof I affix my signature in presence of two witnesses.

WARREN C. FISHER.
